UNITED STATES PATENT OFFICE.

HARRY E. BROWN, OF GRENOVA, KANSAS, ASSIGNEE TO BROWN MACHINE COMPANY,
OF GRENOVA, KANSAS.

UNDERREAMER.

Application filed June 8, 1921. Serial No. 476,010.

To all whom it may concern:

Be it known that I, HARRY E. BROWN, a citizen of the United States, residing at Grenola, in the county of Elk and State of Kansas, have invented a new and useful Underreamer, of which the following is a specification.

This invention relates to under-reamers for use in the drilling of wells, one of the objects of the invention being to provide an under-reamer utilizing cutters which cannot become detached from the tool while in use but which, in the event of breakage, will fall into a hood or extension provided on the body of the tool so that the broken part or parts can thus be lifted readily out of the well without necessitating an expensive and oftentimes ruinous fishing operation.

Another object is to provide an underreamer the various parts of which are locked together securely so that there is no danger of separation during the drilling operation.

A still further object is to provide the cutters with an abutment for receiving the thrusts therefrom during the cutting operation this abutment being in the form of a core which is reversible so as to present unworn surfaces to the cutters after a portion of the core has become worn as the result of use.

A still further object is to provide a draw head of novel construction for holding the cutters in active positions, this draw head being shiftable by means of a suitable key for the purpose of releasing the cutters so as to allow the cutters to be removed for sharpening or replacement.

Another object is to provide the underreamer with supplemental means for holding the cutters in proper relation to the body of the tool should any of the working parts of said tool become broken.

With the foregoing and other objects in view which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

In said drawings—

Figure 1 is a view partly in section and partly in elevation of the under-reamer, the key used for loosening the cutters being shown in position.

Figure 2 is an enlarged section on line 2—2, Figure 1.

Figure 3 is an enlarged section on line 3—3, Figure 1.

Figure 4 is an enlarged section on line 4—4, Figure 1.

Figure 5 is an enlarged section on line 5—5, Figure 1.

Figure 6 is an enlarged section on line 6—6, Figure 1.

Referring to the figures by characters of reference 1 designates the body of the under-reamer, the same being provided at its lower end with spaced parallel bridles 2 which connect the body to an end cage or sleeve 3. In this cage or sleeve is seated a tubular plug 4 held in place by a tangential pin 5 which can be secured by a cotter 5' or the like, as shown in Figure 2. Longitudinal passages 6 are formed between this plug and the sleeve and a central bore 7 is provided in the plug for the reception of a tube 8 constituting a protecting sleeve or jacket for a key in the form of a rod 9. This rod has an eye 10 at its lower or outer end while its inner end is screw threaded as shown at 11 for the purpose hereinafter set forth.

Each of the bridles has its side walls substantially parallel as shown in Figure 3 and formed along the upper portion of each side of each bridle is a retaining rib 12 the lower end of which terminates above the top of the cage or sleeve 3. These ribs are slidably engaged by lateral projections 13 on the sides of cutters 14, the said cutters being slidable longitudinally between the bridles and, when moved downwardly sufficient distances toward the sleeve or cage 3, being adapted to become disengaged from the ribs 12. The lower portions of the cutters are in the form of blades 15 offset outwardly as shown and the upper portion of each of the cutters has its outer surface inclined upwardly and inwardly as shown at 16.

Each cutter has an inwardly extending shoulder 17 at the upper end of the offset blade portion 15 and these shoulders are adapted to be engaged by upwardly extending lugs 18 formed on a draw head 19 located between the bridles 2. A coiled spring 20 is seated on the plug 4 and bears upwardly against the draw head 19 so as to hold the lugs 18 normally pressed against the shoulders 17, thus to force the upper ends of the cutters against those portions of the body 1 between the upper ends of the bridles and at the same time prevent the offset portions 15 from swinging inwardly.

Notches 21 are formed in the bridles as shown in Figure 3 and are so located that when the draw head 19 is pulled downwardly from between the cutters, it can be rotated to bring the lugs into the notches 20 and thus hold the spring 20 under compression. This shifting of the draw head can be effected by means of the key 9 as hereinafter pointed out.

The body 1 has a longitudinal bore 22 extending therewith from its lower end and in the upper portion of this bore is mounted a sleeve 23 held against relative movement by a tangentially arranged pin 24. The sleeve has an angular opening 25 extending therethrough and slideable within this opening is an elongated nut 26 engaged by the threaded upper end portion of a draw bar 27. The lower end of this draw bar has an angular head 28 seated in a recess 29 in the bottom of the draw head 19 and a threaded recess 30 is formed in the lower end of the draw bar and is adapted to receive the threaded end of the key 9.

Mounted within the body 1 is a core 31 preferably formed of hardened steel and having tapered ends 32. Cylindrical bores 33 are extended into the core from each end thereof and are connected at the center of the core by an angular passage 34. The draw bar 27 is slidably mounted in this core and has an intermediate angular portion slideable within the angular passage 34, as shown at 35 so that the draw bar is thus held against rotation. The core is prevented from rotating by a tangential pin 36 mounted in the body.

A coiled spring 37 is mounted on the draw bar and bears at one end within the upper bore 33 and at its other end against the nut 26. Thus the nut is held normally pressed upwardly and the spring will exert a constant pull through the draw bar 27 and the draw head 19 against the shoulders 17 on the cutters.

When it is desired to place the cutters in or remove them from position the key 9 is inserted into engagement with the draw bar 27 and is then anchored to a rigid structure after which the body 1 is pulled upwardly. This will cause the two springs 20 and 37

to be placed under compression and will result in the downward movement of the draw head 19 away from the shoulders 17. The draw head can then be rotated to bring the lugs 18 into the notches 21 whereupon the cutters can be slid downwardly out of engagement with the ribs 12 and thus lifted from between the bridles. The cutters after being sharpened can be replaced between the bridles or new ones can be placed in position after which the draw head 19 can be rotated to disengage the lugs 18 from the notches 21 and thus allowed to move against the shoulders 17 and hold the cutters elevated.

When the tool is in use the key 9 and the sleeve 8 are of course removed. The cutters are slid downwardly against the draw head 19 until the shoulders 17 are brought below the core 31 whereupon the cutters can swing inwardly between the bridles and thus be inserted with the body 1 into the casing. After the cutters have passed beyond the lower end of the casing they will be slid upwardly and swung laterally by the spring controlled draw head and will operate efficiently for the purposes intended. During the reaming operation the hard steel core 31 constitutes a backing or abutment for the cutters and receives the thrusts therefrom. When the tool is pulled upwardly the cutters will be forced longitudinally of the bridles until their shoulders 17 clear the core 31 whereupon they will swing inwardly between the bridles and thus move upwardly in the casing with the body. Should one of the cutters become broken while in use or should any of the other parts break, the same will fall into the spaces between the bridles and above the cage or sleeve 3 so that by raising the tool the broken part will be elevated therewith and it will be unnecessary to fish for it.

By rotating the draw bar within the nut 26 the tension of the spring 37 can be varied and by removing the pin 36 the core 33 can be removed and reversed should the lower end thereof become unduly worn as a result of its frictional engagement with the cutters.

By having the spring 20 the cutters will be held securely in place even though the draw bar or its spring 37 should break or the core 31 should work loose and thus said spring acts as a supplemental safety device which is very desirable although not absolutely essential.

What is claimed is:-

1. In an underreamer the combination with a body, and bridles extending therewith, of cutters between and slidably engaging the upper portions of the bridles, a core interposed between the cutters and projecting between the bridles, and yieldingly supporting means engaging the cutters for

holding them normally positioned between the upper portions of the bridles and in engagement therewith.

2. In an under-reamer the combination with a body, and bridles extending from the body, of cutters slidably and tiltably mounted between the bridles, cooperating means upon the cutters and the upper portions of the bridles for limiting the outward movement of the cutters relative to the bridles, a core within the body and extending between the cutters for limiting their inward movement, and yieldingly supported means for holding the cutters between the upper portions of the bridles and in contact with the core.

3. In an under-reamer the combination with a body, and bridles extending from the body, of cutters tiltably and slidably mounted between the bridles, cooperating means upon the cutters and the upper portions of the bridles for limiting the outward movement of the cutters relative to the bridles, a core projecting between the cutters when in their normal positions, a yieldingly supported draw head between the bridles for holding the cutters in normal position, and means upon the bridles and cooperating with the draw head for engaging and holding the draw head out of cutter supporting position.

4. In an under-reamer the combination with a body, and bridles extending from the body, of a core extending between the bridles and terminating above the sleeve, cutters tiltably and slidably mounted between the bridles, cooperating means upon the cutters and the upper portions of the bridles for limiting the outward radial movement of the cutters, said core constituting an abutment for limiting the inward radial movement of the cutters, and a yieldingly supported draw head for supporting the cutters in engagement with the core and the upper portions of the bridles.

5. In an under-reamer the combination with a body, and bridles extending from the body, of a core extending between the bridles and terminating above the sleeve, cutters tiltably and slidably mounted between the bridles, cooperating means upon the cutters and the upper portions of the bridles for limiting the outward radial movement of the cutters, said core constituting an abutment for limiting the inward radial movement of the cutters, and a yieldingly supported draw head for supporting the cutters in engagement with the core and the upper portions of the bridles, and means for sliding the draw head toward the sleeve against the action of its yielding supporting means and for rotating the draw head, there being notches within the bridles to receive the rotated draw head to hold it against return movement.

6. In an under-reamer the combination with a body, and bridles extending from the body, of guide ribs upon the upper portions of the bridles, cutters slidable and tiltably between the bridles, means thereon and cooperating with the ribs for limiting the outward radial movement of the cutters, and a reversible core detachably seated within the body and projecting between the cutters, said core constituting an abutment for limiting the inward radial movement of the cutters.

7. In an under-reamer the combination with a body, and bridles connected to the body, of cutters tiltably and slidably mounted between the bridles, cooperating means upon the cutters and bridles for limiting the outward radial movement of the cutters, and a reversible core detachably mounted in the body and projecting between the cutters, said core constituting an abutment for limiting the inward radial movement of the cutters.

8. In an under-reamer a body, bridles extending therefrom, a tubular core reversibly and detachably mounted in the body, cutters tiltably and slidably mounted between the bridles and limited in their inward movement by the core, cooperating means upon the cutters and bridles for limiting the outward radial movement of the cutters, a draw bar slidably mounted within the core, a draw head movable therewith and engaging the cutters, said draw head being disposed below the end of the core, and yielding means within the core and body for supporting the draw bar and the draw head to maintain the cutters normally upon the core and between the upper portions of the bridles.

9. In an under-reamer a body, bridles extending therefrom, cutters removably mounted between the bridles and tiltably and slidably relative thereto, means for limiting the outward radial movement of the cutters, a core within the body and projecting between the cutters for limiting their inward movement, a draw bar slidably within the core, a draw head connected thereto and normally engaging and supporting the cutters between the bridles, a nut slidably within the body and adjustably engaged by the draw bar, and a spring engaging the nut and core for yieldingly supporting the draw bar and draw head and the cutters engaged by the draw head.

10. In an under-reamer a body having a tubular portion, cutters movably mounted in the body, and a relatively hard core within the body and extending between and constituting an abutment for the cutters.

11. In an under-reamer a body, cutters movably mounted in the body, and a relatively hard core within the body and extending between and constituting an abutment for the cutters.

12. In an under-reamer a body, cutters movably mounted therein, and a relatively hard core removably mounted in the body and extending between and constituting an abutment for the cutters.
13. In an under-reamer a body, cutters movably mounted therein, and a relatively hard core removably and reversibly mounted in the body and extending between and constituting an abutment for the cutters.
14. In an under-reamer a body having a tubular portion, a draw bar slidable within said portion, yielding means within the said body for normally supporting the bar in one position, and co-operating means upon the draw bar and within the body for holding the bar against rotation in the body while in said normal position.
15. In an under-reamer a body, a draw bar slidable within the body, a spring in the body for normally supporting the draw bar in one position, co-operating means upon the draw bar and in the body for holding the body and draw bar against relative rotation while the bar is in said normal position, a nut upon the bar for adjusting the tension of the spring, and means in the body for holding the nut against rotation, said nut being slidable with the bar.
16. In an under-reamer a body, cutters movably connected thereto, and means at the lower end of the body for receiving and engaging the cutters or portions of the cutters when separated from the body while in use.
17. In an under-reamer a body, cutters movably connected thereto, and a cage carried by the lower end of the body for catching broken cutters while in use.
18. In an under-reamer a body, cutters removably connected thereto, a spring controlled draw-bar in the body, a head upon the draw-bar normally clamping against the cutters to hold them in active positions, means for shifting the draw-bar and head against the action of the spring to release the cutters, and means engaged by the head of the draw-bar when rotated while in releasing position, for holding said head and draw-bar against return to normal positions.
19. In an under-reamer a body, a draw-bar slidable in the body, an elongated angular nut thereon, means in the body and slidably engaged by the nut for holding the nut against rotation, a spring engaging the nut for holding the bar yieldingly in normal position, cooperating means on the bar and body for holding the bar normally against rotation, and means for shifting the bar longitudinally out of engagement with said holding means to rotate the bar relative to the nut and vary the tension of the spring.

In testimony that I claim the foregoing as my own, I have hereto affixed my signature in the presence of two witnesses.

HARRY E. BROWN.
